DRAFTSMAN'S SPACING DEVICE

Ernst Richter, Farmingdale, N. Y.

Application March 22, 1955, Serial No. 495,995

2 Claims. (Cl. 33—110)

The present invention relates to draftsman's spacing devices of the character which will accurately determine a succession of positions of a drafting implement for the purpose of drawing lines such as section lines or other lines requiring periodic equal spacing.

A further purpose is to facilitate step by step motion of a drafting implement along a T square or other straight edge or across a piece of drawing paper or a drawing board or template.

A further purpose is to accomplish the spacing with simple, reliable and inexpensive mechanism.

Further purposes appear in the specification and in the claims.

In the drawings I have chosen to illustrate one only of the numerous embodiments in which my invention may appear, selecting the form shown from the standpoints of convenience in illustration, satisfactory operation and clear demonstration of the principles involved.

Figure 1 is a perspective of the spacing device of the invention.

Figure 2 is a section along the line 2—2 of Figure 1.

Figure 3 is a side elevation partly in section along the line 3—3 of Figure 4.

Figure 4 is a fragmentary plan view showing the device of the invention applied to a T square with an associated triangle.

Figure 5 is a central axial section on the line 5—5 of Figure 4 similar to Figure 3 but showing the foot in the relative forward position with respect to the base where Figure 3 shows the foot relatively rearward with respect to the base.

Figure 6 is a perspective of a variation.

Describing in illustration but not in limitation and referring to the drawings:

In drafting, both inking and pencil work, in making jigs and templates, in spacing center marks for drilling holes, it is frequently necessary to produce a large number of lines which are equally spaced. This may be necessary for the purpose of sectioning or for other purposes in making drawings, or to locate holes, or for projection. This work has been very tedious when applied with accurate measurement, leading to the practice of putting in lines by estimation, which in some cases leads to very inaccurate work.

The device of the invention makes it possible to obtain accurate step-by-step spacing in a simple, reliable and effective manner.

In accordance with the invention, each step advances the implement a predetermined but adjustable step distance, so that the mechanism can be set for any desired predetermined spacing.

The spacing device may be applied directly to the drawing paper or to the drawing board or template, but will preferably be used on a T square or other straight edge. It may operate either longitudinally or transversely or at an angle, as desired.

The mechanism of the invention comprises a body or

2

base 20 which may suitably be of wood, plastic or metal and desirably has a lower surface covered with a frictional material such as leather or felt 21. The frictional material is desirably chosen so as to limit free sliding but 5 not prevent sliding when positive force is applied.

The body 20 is recessed at the interior at 22 to form an interior well having longitudinal guiding side walls 23 which receive and guide a foot 24 suitably of wood, metal or plastic as desired, and covered with a frictional 10 layer 25 on the bottom which may similarly be of leather or felt having properties as above described. The foot is capable of raising and lowering slightly and moving back and forth while engaging the guiding walls 23. It will be noted that the plan area of the foot is less than that of the body.

The body at the rear of the device supports a bracket 26 extending upward and at the top mounting a transverse horizontal pivot pin 27 which pivots a bellcrank operating lever 28. The bellcrank operating lever has a top lever portion 30 provided with an operating button 31 for engagement by the hand and which is suitably positioned nearly above the center of the foot. The button 31 is conveniently recessed at 32 so that the finger will not slip off and is held by a rivet 33.

The operating lever has lower extending ends 34 which engage stops 35 on the bracket and the operating lever is urged toward stop position by a torsion spring 36 having a coil surrounding the pivot pin 27 and having an end 37 engaging the lower side of the operating lever and an opposed end 38 which rests on the top of a transverse pivot pin 40 mounted on brackets 41 which are secured to the body on either side of the opening containing the foot.

The operating lever at the outer end has a suitably metallic extension 42 which engages a follower roller 43 pivotally mounted on a pin 44 which extends across a slotted second lever 45 suitably of L-shape. The second lever intermediate its ends rests and slidably pivots on pivot pin 40 and is held against pivot pin 40 by a leaf spring 46 engaging the lower side of pivot pin 40 and mounted on a bracket 47 on the bottom of the second lever.

The end of the second lever 45 remote from the follower roller is suitably slotted at 48 and mounts a transverse pivot pin 50 which pivotally connects to a suitable L-shaped link 51. The link 51 has a branch 52 extending upward and a branch 53 which extends in scissors relation through the slot 48, engaging the under side of pivot pin 40, and at the opposite end pivotally engages in 50 a pin 54 which extends across a slot 55 in the foot. The pivot pin is anchored in place by a slotted cover plate 56 secured to the top of the foot.

The foot is relatively retracted forwardly by helical tension spring 57, which at the forward end engages spring 55 abutment 58 on the body and at the rearward end engages spring abutment 60 on the foot. Spring abutment 60 has a head 61 at the top and extends through a longitudinal slot 62 on a limiter strip 63 which at the forward end is slotted at 64 and held in adjustable position by an adjustment screw 65 secured to the body.

The body at suitable points on the top and suitably on either side carries screw holes 66 which receive retaining screws 67 which secure brackets 68 having slots 70 engaged under the screws. The brackets at the outer ends have screws 71 which are suitably anchored as by engagement in holes in a drafting implement, for example a triangle 72, whose lower edge 73 is in slidable relation with one of the longitudinal edges 74 of T-square 75 having cross arm 76.

On the opposite side of the body, screw 77 secures spring 78 which extends down along the opposite longi-

tudinal side 80 of the T square and spring urges the triangle into maintaining engagement with the T square.

In operation, the adjustment screw 65 is released and the adjustment strip 63 is set so that the limit on motion of the foot as shown in Figure 3 will predetermine the correct step distance between lines, and then screw 65 is tightened. The triangle or the like is secured as by applying screws 71 in suitable holes in the triangle and securing brackets 68 by screws 67. The spacing device is then placed in position along the straight edge and the device is ready to operate. The operator presses down on button 31, depressing operating lever 30 as far as it will go against the action of spring 36. This forces follower roller 43 down and tends to rock second lever 45 counterclockwise to the position shown in Figure 3, causing the rearward end of the second lever to deflect the link counterclockwise, moving the foot 24 relatively rearward with respect to the body and at the same time applying relatively greater pressure to the foot than the pressure on the body. The effect, therefore, is to tend to make the foot hold due to its higher pressure, while the body having a larger pressure area but being under a lower pressure, slides forward as shown in Figure 3. In effect the foot stays still and the body moves forward while extending the tension spring 57.

When the pressure of the finger is released from the button 31, spring 36 tends to move the operating lever 28 clockwise until it is limited by the stop 35. Spring 57 retracts the foot with respect to the body to the position of Figure 5, and at the same time the pressure on the foot is relaxed and the foot is free to raise slightly due to the weight of the device and slide forward. The link 51 and the second lever 45 are retracted to the position of Figure 5.

During all of this step by step motion, slight sliding occurs between the second lever and the link with respect to pivot pin 40, the scissors or crossing relation of the second lever and the link and the action of leaf spring 46 tending to hold the second lever and the link against the pivot pin.

Thus it will be evident that when pressure is applied downward at a position close above the foot and near the center of the body the effect of the linkage is to apply relatively higher pressure on the foot and relatively lighter pressure on the body and move the body forward while holding the foot stationary. When the pressure on the operating lever is relieved the body remains stationary and the foot moves forward because the concentration of pressure downward on the foot is relieved, the foot is pulled forward and the larger bottom engaging area of the body holds the body stationary.

Thus accurate step by step motion can be obtained. The draftsman will bring the triangle or other drafting implement to the position for the first line, draw the

first line, and then press down on the button and allow the button to retract moving the device to the position for the next line. The next line is drawn and then the button is pressed again and allowed to retract, moving to the position for the next line. For different spacing it is merely necessary to adjust the strip 63 by changing the position of adjustment screw 65.

When locating holes, a center punch 81 mounted on spring strip 68' receives a hammer blow to make a center punch mark at each step of advance on the work. The strip is held by screw 67.

In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a draftsman's spacing device, a body slidable along a drawing board or the like, and having an interior opening, a foot positioned in the interior opening of the body, and slidable along the drawing board, means for guiding the foot in relative forward and backward motion with respect to the body, an operating lever pivotally mounted on the body and swingably movable from a position above the foot toward and away from the foot, a second lever operatively engaging the operating lever near its end remote from the pivotal mounting, a link pivotally connected to the second lever at the end of the second lever remote from the engagement of the second lever with the operating lever, the link being pivotally connected to the foot at the end of the link remote from the second lever, and a slidable pivot on the body for the second lever and the link, whereby the foot advances and retracts with respect to the body and concurrently shifts relative pressure from the foot to the body and vice versa.
2. A spacing device of claim 1, in which the second lever and the link extend in scissors relation and the slidable pivot is located between the crossing parts of the second lever and the link.
